UNITED STATES PATENT OFFICE.

ALFRED O. LINDSEY, OF CHARLESTOWN, MASSACHUSETTS.

MACHINE FOR MANUFACTURE OF SHOE-BINDING.

Specification forming part of Letters Patent No. 42,300, dated April 12, 1864.

To all whom it may concern:

Be it known that I, ALFRED O. LINDSEY, of Charlestown, in the county of Middlesex and State of Massachusetts, have invented a new and useful machine for printing skins and cutting the same into bands to be used for making shoe-binding; and I do hereby declare the same to be fully described in the following specification, and represented in the accompanying drawings, of which—

Figure 1. denotes the machine in side elevation; Fig. 2, a top view of one of the bands made by the machine; Fig. 3, a top view on an enlarged scale of some of the endless supporting bands, the printing-rollers, and the rotary knives of the said machine.

The nature of my invention consists in the combination of a series of endless carrying-bands, arranged at proper distances apart, and duly supported on and by rotary drums or rollers, a rotary bearing or bed drum, a series of rotary cutters, and a printing, marking, or stamping apparatus, composed of a series of striping-rollers, and a reservoir for them to revolve in, the whole being arranged and so as to operate in manner as hereinafter explained.

In Figs. 1 and 3 of the drawings, B B B are a series of endless cords or carrying-bands, arranged at equal distances asunder and around two drums, 3 4, and so as to run against its bed-drum 5, and also two auxiliary and supporting or guiding rollers, G g, the said drums and rollers being arranged with respect to one another and with a frame, A, as shown in Fig. 1. A series of striping-rollers, R R R, provided with an ink-reservoir, C, into which they partially enter, is arranged with their peripheries between the several bands B B, and so as to roll against a skin while it may be passing between the said peripheries and the drum 5. Each of the striping-rollers should not only be separate from that or those next adjacent to it, but be provided with a spring or means of keeping it up in close contact with the skin while such skin may be in the act of being colored or striped by such rollers. Furthermore, there is a series of circular knives, K K, arranged on one shaft and at equal distances apart, they being placed below the drum 5 and so that their cutting peripheries may rest against the same and be arranged

with respect to the striping-rollers and the carrying-bands as shown in Figs. 1 and 3. An endless belt, c, going around a pulley, b, and a drum-pulley, 2, serves to put the cutters in revolution, the pulley b being on one end of the shaft d of the cutting-knives. The pulley 2 is fixed on a shaft, f, which carries a pulley, h, about which and a pulley, l, an end band, i, travels. The pulley l is carried by a driving-shaft, k, on which there is another pulley, l, around which and a pulley, m, carried by another shaft, n, an endless belt, o, operates. The drum 3 is driven by an endless belt, p, which goes around two pulleys, q r—one being on the shaft n and the other being fixed to the shaft of the said drum. In Fig. 1 the pulleys l m and the endless belt o are represented in red lines.

When the shaft k is revolved in the direction represented by the arrow in Fig. 1, the several operative parts of the machine will be put in motion in such manner that whenever a skin is laid on the bands B B and between the drums 3 and 5 such skin will be moved forward between the said bands and the drum 5 and against the series of cutters and the series of striping-rollers, and after having been cut into strips and had each strip striped, as shown in Fig. 2, such skin or portions thereof will be carried over the drum 5 and by it be discharged from the machine, a chute, T, if desirable, being applied to the drum to facilitate the discharge of the skin or strips therefrom. The strips, after passing from the machine and being dried, are to be cut in two longitudinally along their middles. The parts so cut, when overlapped and joined or connected together at their ends and reduced to one uniform thickness, constitute the article denominated "shoe-binding."

What I claim as my invention is—

The machine or combination substantially as above described, such consisting of the endless series of carrying bands B B B, the bed-drum 5, the series of rotary cutters K K K, and the striping mechanism or rollers R and reservoir C, arranged and so as to co-operate, and supplied with operative mechanism, substantially as hereinbefore explained.

ALFRED O. LINDSEY.
